FUEL PUMP

Ward D. Smith, Dearborn, Mich., assignor to F. L. Jacobs Co., Detroit, Mich., a corporation of Michigan

Application April 20, 1946, Serial No. 663,660

8 Claims. (Cl. 103—150)

1

The present invention relates generally to internal combustion engines and it has particular relation to a fuel pump.

Fuel pumps employing pulsating diaphragms are generally used in motor vehicles for the purpose of supplying fuel to the carburetor. These pumps are operated, as a rule, by cam means on the engine cam shaft, and the present invention is concerned with a fuel pump of this general character.

One object of the present invention is to provide an improved fuel pump of the above generally indicated type employing a pulsating diaphragm, which is simple in construction, economical of manufacture and assembly, and which is reliable and efficient in operation.

Another object of the invention is to provide a fuel pump of the above generally indicated type having an improved resilient valve element for controlling the flow of fuel to the pump.

Another object of the present invention is to provide an improved fuel pump of the above indicated type having improved resilient valve means readily accessible for repair or replacement.

Other objects of the invention will become apparent from the following specification, from the drawings relating thereto, and from the claims hereinafter set forth.

For a better understanding of the invention reference may be had to the drawings wherein:

Figure 1 is a plan view of a fuel pump constructed according to one form of the invention, showing the cover and associated screw removed;

Figure 2 is a cross sectional view taken substantially along the line 2—2 of Figure 1 showing the cover and associated screw in place;

Figure 3 is an enlarged fragmentary cross sectional view taken substantially along the line 3—3 of Figure 4;

Figure 4 is a reduced partial cross sectional view taken substantially along the line 4—4 of Figure 3;

Figure 5 is a partial cross sectional view of a fuel pump constructed in accordance with a modified form of the invention; and

Figure 6 is a reduced partial cross sectional view taken substantially along the line 6—6 of Figure 5.

Referring to Figs. 1 and 2 of the drawings, the pump comprises a casing having a lower part 10 and an upper part 12, and these parts of the casing have flanges 14 and 16 respectively, fastened together by screws 18. The casing thus provided is divided by a diaphragm 20 having a marginal portion 22 clamped between the flanges 14 and

2

16. The diaphragm is constructed of suitable material such as synthetic rubber having high resistance to the action of hydrocarbon fuel and it is flexible so that it may be moved relative to its marginal portion. At its center the diaphragm is held between two discs 24 and 26 which are connected at their centers by a pin 28.

During operation of the pump the diaphragm moves upwardly and downwardly or in other words, pulsates, and this movement of the dia-

10 phragm may be effected by any suitable means, for instance, an arm 30 pivoted intermediate its ends on a pin 32 in the lower part 10 of the casing and have an operative connection at its inner end

15 with the pin 28. This connection at the inner end of the arm 30 is such as to allow the stroke of the diaphragm 20 and pin 28 to vary in accordance with the fuel pressure above the dia-

20 phragm, or in other words, if the pressure above the diaphragm increases, the stroke will be shortened whereas if the pressure above the diaphragm decreases, the stroke will be lengthened. Move-

25 ment of the arm 30 may be effected by a stem 34 operating from the engine cam shaft and which

seats in a socket 36 formed on the outer end of

the arm 30.

The upper part 12 of the casing includes an inner cylindrical wall 38 and an outer cylindrical wall 40. The inner cylindrical wall 38 defines internally thereof an inner vapor and fuel cham-

30 ber 42 and co-operates with the outer cylindrical wall 40 to define an outer vapor and fuel chamber 44. A partial cylindrical wall 46 disposed

35 within the outer vapor and fuel chamber 44 supports a cylindrical filter 48 upon its upper end.

35 The filter 48 is positioned by 3 angularly spaced ribs 49. Fuel enters the outer chamber 44 by means of a fuel inlet 50 and passes through the filter 48 disposed in said chamber. It then flows from the outer chamber 44 to the inner chamber 42 by means presently to be described, and from the inner chamber it flows through a connection

50 52 leading to the engine carburetor.

Referring to Figs. 1 and 3, wall 54 integrally formed on the upper part 12 of the casing ex-

45 tends thereacross and is disposed in spaced relation to the base or lower end thereof and co-

50 operates with the lower part of the wall 40 and the diaphragm 20 to define a chamber 56. The wall 54 has an opening 58 connecting the inner vapor and fuel chamber 42 with the chamber 56

55 and is also provided with a plurality of openings 60 outwardly thereof communicating with the outer vapor and fuel chamber 44 and with the chamber 56.

A resilient valve disk 62 is disposed within the chamber 56 and positioned against the wall 54 on posts 64 integrally formed on said wall 54. The valve disk 62 is constructed of suitable material such as of synthetic rubber having high resistance to the action of hydrocarbon fuels. A plate 66 is received over the lower ends of posts 64 and is held in a position to urge the valve 62 against the wall 54 to form an annular seal between said wall 54 and said plate 66 outwardly of the opening 58 and inwardly of the openings 60. The plate 66 is held in this position by deforming the lower ends of the posts 64 as shown at 68 to give a riveting effect. The plate 66 is provided with an opening 70 disposed centrally thereof for communication with the chamber 42 through the opening 58.

The valve disk 62 is provided with an annular sealing bead 72 engaging the plate 66 outwardly of the opening 70 and has an annular channel 74 formed therein outwardly of the bead 72. The valve disk 62 has a plurality of apertures 76 formed therein which communicate with the channel 74 and the opening 58 in the wall 54. The valve disk 62 is also provided with an outer annular channel 78 formed in the side thereof adjacent the wall 54 and disposed outwardly of the posts 64 and communicating with the opening 60 formed in the wall 54. Adjacent the channel 78 and outwardly thereof the valve disk 62 is provided with an annular bead 80 for engaging the wall 54 to close the openings 60.

Referring to Fig. 1, the upper end of the casing is closed by a cover 82 having an annular sealing gasket 84 which engages the upper end of the cylindrical wall 40. This cover is held in place on the casing by a centrally disposed screw 86 extending through the cover 82 and having a threaded engagement with an integral portion formed on the upper end of the inner cylindrical wall 38 which serves to close the upper end of the inner vapor and fuel chamber 42.

During the operation of the pump, the downward movement of the diaphragm 20 causes the portion of the valve disk disposed outwardly of the posts 64 to be flexed downwardly unseating the annular sealing bead 80 from the wall 54 and causing fuel to flow inwardly through the inlet opening 50 into the outer fuel and vapor chamber 44, through the filter 48, and then through the openings 60 and past the unseated bead 80 into the chamber 56. During this downward movement the annular sealing bead 72 is held in engagement with the plate 66 to close the opening 70 centrally thereof. Upon upward movement of the diaphragm 20 the sealing bead 80 seats against the wall 54 to close the opening 60 and the portion of the valve disc inwardly of the posts 64 is flexed upwardly unseating the annular sealing bead 72 from its engagement with the plate 66 and permitting flow of fuel from the chamber 56 through the opening 70, past the unseated bead 72, through the openings 76, the opening 58, and into the inner chamber 42 from which it flows out through the outlet connection 52 to the carburetor. It should be understood that the resiliency of the valve disc tends to cause the sealing beads to return to sealing contact with the metal surfaces they are adapted to engage.

The modification illustrated in Figures 5 and 6 differs from the above described embodiment in that the valve disc 90, corresponding to the valve 62, is mounted on pins 92 carried by a plate 94 corresponding to the plate 66, rather than on posts 64 as in the above described embodiment.

The plate 94 is mounted in the casing by the engagement of a plurality of radially extending projections 96 formed on the plate 94 in corresponding slots 98 formed in the casing. The plate 94 is held in proper position against the upper end of the slots 98 by a snap ring 100 which is snapped over the arcuately extending shoulders 102 which serve to hold the snap ring 100 in place. Plate 94 is provided with a centrally disposed aperture 104 corresponding to the opening 70 and is also provided with a plurality of apertures 106 disposed outwardly of the pin 92 which serve to allow the flow of fuel drawn through the openings 108, corresponding to the opening 60, to pass to the lower side of the plate 94. In the above described embodiment there are no openings corresponding to openings 106 for the reason that fuel flowing through the openings 60 may flow around the outer periphery of the plate 66 and thus to the lower side thereof.

Although only two specific forms of the invention have been illustrated and described in detail it will be apparent to those skilled in the art that various modifications may be made without departing from the scope of the appended claims.

What is claimed is:

1. In a fuel pump, a resilient valve disk having an inner annular channel portion formed on one side thereof, a plurality of openings through said disk communicating with said channel portion, an annular bead disposed adjacent said channel portion and inwardly thereof, an outer annular channel portion formed in the other side of said valve disk, and an annular bead disposed adjacent said outer channel portion and outwardly thereof.

2. In a fuel pump, a casing including an inlet chamber and an outlet chamber, a wall on said casing having a first opening communicating with one of said chambers and an additional opening between said first opening and the periphery of said casing and communicating with the other of said chambers, a plate mounted on said wall in spaced relation thereto and having an aperture adapted to communicate with said first opening, and a resilient valve disk between said wall and said plate having an opening adapted to connect said aperture and said first opening, said disk having an annular portion surrounding said first opening and extending between said first opening and said additional opening and providing a seal between said wall and said plate, said resilient valve disk inwardly and outwardly of said annular portion being free to flex so as to alternately open and close said aperture and said additional opening in such a manner that unidirectional flow is provided from said inlet chamber past said valve disk and into said outlet chamber.

3. In a fuel pump, a casing including an inlet chamber and an outlet chamber, a wall on said casing having a first opening communicating with one of said chambers and an additional opening between said first opening and the periphery of said casing communicating with the other of said chambers, a plate mounted on said wall and disposed substantially parallel and in spaced relation thereto, said plate being formed to expose said additional opening and to cover said first opening and having an aperture adapted to communicate with said first opening, and a resilient valve disk between said wall and said plate having an opening adapted to connect said aperture with said first opening, said disk having an annular portion surrounding said first open-

ing and extending between said first opening and said additional opening and providing a seal between said wall and said plate, said resilient valve disk inwardly and outwardly of said annular portion being free to flex so as to alternately open and close said aperture and said additional opening in such a manner that unidirectional flow is provided from said inlet chamber past said valve disk and into said outlet chamber.

4. In a fuel pump, a casing having an inlet chamber and an outlet chamber, a wall on said casing having a first opening communicating with said outlet chamber and an additional opening between said first opening and the periphery of said casing and communicating with said inlet chamber, a plate mounted on said wall and disposed substantially parallel and in spaced relation thereto, said plate being formed to expose said additional opening and to cover said first opening and having an aperture therein adapted to communicate with said first opening, and a resilient valve disk disposed between said wall and said plate, having an opening adapted to connect said aperture with said first opening, said disk having an annular portion surrounding said first opening and extending between said first opening and said additional opening and providing a seal between said wall and said plate, said resilient valve disk outwardly of said annular portion being free to flex to alternately open and close said additional opening to provide for unidirectional flow from said inlet chamber past said valve disk, said resilient valve disk inwardly of said annular portion being free to flex so as to alternately open and close said aperture to provide for unidirectional flow through said aperture past said valve and into said outlet chamber.

5. In a fuel pump, a casing having an inlet chamber and an outlet chamber, a wall on said casing having a first opening communicating with said outlet chamber and an additional opening between said first opening and the periphery of said casing and communicating with said inlet chamber, a plate mounted on said wall in spaced relation thereto, said plate being formed to expose said additional opening and to cover said first opening and having an aperture therein adapted to communicate with said first opening, and a resilient valve disk disposed between said wall and said plate, having an annular portion surrounding said first opening and extending between said first opening and said additional opening and providing a seal between said wall and said plate, said valve disk inwardly of said annular portion having an annular sealing bead adapted to engage said plate outwardly of said aperture and being free to flex so as to alternately establish and break communication between said aperture and said first opening and arranged to provide unidirectional flow through said aperture and into said outlet chamber, said valve disk outwardly of said annular portion having an annular sealing bead adapted to engage said wall outwardly of said additional opening and being free to flex to alternately open and close said additional opening to provide unidirectional flow from said inlet chamber through said additional opening and past said valve disk.

6. In a fuel pump, a casing having an inlet chamber and an outlet chamber, a wall integral with said casing and having a first opening communicating with one of said chambers and an additional opening between said first opening and

the periphery of said casing and communicating with the other of said chambers, said casing being formed to provide circumferentially spaced slots disposed at right angles to said wall, a plate having radially extending projections received in said slots, means mounting said plate disposed substantially parallel and in spaced relation to said wall, said plate having an aperture adapted to communicate with said first opening, and a resilient valve disk between said wall and said plate having an annular portion surrounding said first opening and extending between said first opening and said additional opening and providing a seal between said wall and said plate, said valve disk having an opening adapted to connect said aperture and said first opening, and said resilient valve disk inwardly and outwardly of said annular portion being free to flex to alternately open and close said aperture and said additional opening in such manner that unidirectional flow is provided from said inlet chamber past said valve disk and into said outlet chamber.

7. In a fuel pump, a casing having an inlet chamber and an outlet chamber, a wall on said casing having central opening communicating with one of said chambers and other openings between the central opening and the periphery of said casing and communicating with the other of said chambers, a plate mounted on said wall in spaced relation thereto and having an aperture adapted to communicate with said central opening, and a resilient valve disk between said wall and said plate having an opening adapted to connect said aperture with said central opening, said disk having an annular portion surrounding said central opening and extending between said central opening and said other openings and providing a seal between said wall and said plate, said resilient valve disk inwardly and outwardly of said annular portion being free to flex so as to alternately open and close said aperture and said other openings, said valve disk being so constructed and arranged and associated with said openings in said wall that unidirectional flow is provided from said inlet chamber past said valve and into said outlet chamber.

8. In a fuel pump, a casing including an inlet chamber and an outlet chamber, a wall on said casing having a first opening communicating with said outlet chamber and an additional opening between said first opening and the periphery of said casing and communicating with said inlet chamber, a plate having an aperture adapted to communicate with said first opening, means mounting said plate in parallel and spaced relation to said wall, and a resilient valve disk disposed between said wall and said plate and having an annular portion surrounding one of said openings and extending between said first opening and said additional opening and providing a seal between said wall and said plate, said valve disk having an annular bead at one side thereof resiliently engaging said wall to normally prevent fluid flow through said additional opening, said valve disk also having an opening therethrough adapted to communicate with said first opening and said aperture and having a second annular bead at the other side thereof resiliently engaging said plate to normally prevent fluid flow through said aperture, said resilient valve disk being adapted to flex adjacent said first named annular bead in response to the pressure of fluid within said inlet chamber acting on one side of said disk, to provide unidirectional flow from said inlet chamber through said additional opening and

also being adapted to flex adjacent said second named bead in response to the pressure of fluid acting on the other side of said disk to provide unidirectional flow through said aperture past said second named bead and into said outlet chamber, and means for varying the fluid pressure on said other side of said resilient valve disk.
